UNITED STATES PATENT OFFICE

164,395

CORNER LAMP

Elizabeth J. Williams, Westchester, Ill.

Application October 7, 1950, Serial No. 12,485

Term of patent 3½ years

(Cl. D48—4)

To all whom it may concern:

Be it known that I, Elizabeth J. Williams, a citizen of the United States, residing at Westchester, in the county of Cook and State of Illinois, have invented a new, original, and ornamental Design for a Corner Lamp, of which the following is a specification, reference being had to the accompanying drawing, forming a part thereof, in which

Fig. 1 is a front perspective view of a corner lamp, showing my new design;

Fig. 2 is a rear perspective view thereof;

Fig. 3 is a top plan view to a somewhat larger scale; and

Fig. 4 is a side elevational view of Fig. 3.

I claim:

The ornamental design for a corner lamp, substantially as shown.

ELIZABETH J. WILLIAMS.
